UNITED STATES PATENT OFFICE

THOMAS J. POWER, OF MILWAUKEE, WISCONSIN, ASSIGNOR, BY MESNE ASSIGNMENTS, TO UNITED STATES HOFFMAN MACHINERY CORPORATION, OF NEW YORK, N. Y., A CORPORATION OF DELAWARE

DRY CLEANING WASHER AND THE LIKE

Application filed March 17, 1930. Serial No. 436,328.

This invention relates to improvements in dry cleaning washers and the like. It is the object of the invention to minimize fire and explosion hazard by providing a washer in which a special door is designed to release, independently of the main washer door, all products of combustion produced within the washer while protecting the operator from the discharge of such products.

10 It is my further purpose to provide a main door for the washer with a spring catch whereby such door is self-locking when closed and I propose further to provide the explosion door at the rear of the washer with 15 an arm which serves to support the main door when that door is open, and to initiate a closing movement of the main door in the event of an explosion while the main door is open.

The drawing shows a diagrammatic cross 20 section through a washer drum embodying this invention.

The washer drum is designated at 1 and the cylinder therein is shown in outline at 2.

The top 3 which covers the drum 1 is provided, 25 with two distinct door openings separated by a frame member 4 to which the main or front door 5 is pivoted at 6 and the rear or explosion door is pivoted at 7.

One or the other of the doors is provided 30 with an arm which defines the minimum angle between the doors. In the particular device illustrated, the arm 8 is attached to the explosion door and the design is such that in the open position of the front or main 35 door 5, the center of gravity of such door will just cross a vertical line above hinge 6 before the door rests against arm 8. It will be obvious that any explosion occurring within drum 1 will lift the explosion door, thereby causing arm 8 to tilt the main door 5 sufficiently to cause it to fall by gravity to its 40 closed position.

While the main door will stand open without support, the explosion door will not. It 45 is so designed that it always tends to fall closed by gravity inasmuch as the arm 8 limits the opening movement of the door to a degree such that the center of gravity of the door does not reach a vertical line through 50 the hinge 7. It is, however, always free to

open to release products of combustion and, having released such products, it will fall to its closed position to smother any fire existing within the drum.

When the main door 5 is shut either manually or as the result of explosion, it is locked in its closed position by means of the ordinary spring catch 10 which engages latch plate 11 subject to release by the handle 12.

It will be obvious that an operator is given comparatively great protection in the use of a machine of this type. During operation of the cylinder 2, the door 5 is always locked and any flame escaping from the machine must necessarily escape at the rear under circumstances such that the lifted explosion door protects the operator. If, as rarely happens, the fire or explosion occurs when the front door 5 is resting open, such door will be closed by the explosion and locked, after which any further escape of gases will take place at the rear. The ultimate result of fire or explosion is to leave all doors closed thereby smothering combustion.

I claim:

1. A dry cleaning washer comprising a drum provided with doors centrally pivoted to open upwardly from front and rear sides of the drum, the rear door comprising a self-closing door permanently unlocked and the front door being provided with a self-acting latch mechanism whereby to be locked when closed.

2. A device of the character described comprising a drum having centrally pivoted doors with margins seating at the front and rear sides of the drum, the rear door comprising a self-closing door and the front door being movable to a position in which it will tend to remain open, one of said doors being provided with an arm projecting in the direction of the other door and adapted to limit their mutual angular approach whereby the opening of the rear door will project the open forward door toward its closed position.

3. A device of the character described comprising a cylinder having centrally pivoted front and rear doors, the former being provided with a latch and the latter being

permanently free to open, and an arm upon one of said doors projecting toward the other and adapted to limit the angular approach of the doors to each other, the front door being adapted for support by said arm in an open position and the rear door being limited thereby to a position in which it is self closing.

4. In a dry cleaning washer, the combination with a drum, of a pair of doors guided for opening and closing movement with respect to the drum, one of the doors being provided with a self-acting latch and adjustable to an open position in which it tends to remain, the other of said doors being free to open at all times and being limited to a range of movement in which it invariably tends to close when opened, and motion transmitting means actuated by an opening movement of the free door for dislodging the door with the latch from the position in which it tends to remain.

5. A dry cleaning washer comprising a cylinder, a drum enclosing said cylinder, a pair of doors pivoted on said drum with their hinge lines in substantial parallelism and disposed so that the doors swing toward each other in opening and away from each other in closing, self-acting locking means on one of said doors, and means carried by one of said doors for preventing the door without locking means from swinging past a vertical plane passing through and defined by its own hinge line.

35 6. A dry cleaning washer comprising a cylinder, a drum enclosing said cylinder, a pair of doors pivoted on said drum and disposed so that they swing toward each other in opening and away from each other in closing, self-acting locking means for one of said doors, and the other of said doors being free to open and constructed and arranged to be biased to closed position at all times.

THOMAS J. POWER.
